(57) **CLAIM**

The ornamental design for a photo box frame, as shown and described.

DESCRIPTION

FIG. 1 is a perspective view of a photo box frame showing my new design;

FIG. 2 is a front view thereof;

FIG. 3 is a rear view thereof;

FIG. 4 is a left side view thereof, the right side view being a mirror image;

FIG. 5 is a top view thereof; and,

FIG. 6 is a bottom view thereof.

The dashed lines in FIGS. 1 and 5 are shown for environmental purposes only and form no part of the claimed design.
